CLAIM

The ornamental design for a switch panel for a vehicle, substantially as shown and described.

DESCRIPTION

FIG. 1 is a top, front, and left side perspective view of the switch panel for a vehicle, showing my new design; FIG. 2 is a bottom and left side perspective view thereof; FIG. 3 is a top elevational view thereof; FIG. 4 is a bottom elevational view thereof; FIG. 5 is a left side elevational view thereof; FIG. 6 is a right side elevational view thereof; FIG. 7 is a rear plan view thereof; and, FIG. 8 is a front plan view thereof.

The oblique line shading is intended to illustrate a highly polished and/or reflective surface treatment.

The broken lines in the drawings illustrate the portions of the switch panel for a vehicle, which form no part of the claimed design.
